Thomas Howe

UNITED STATES PATENT OFFICE.

WALTER G. CRAIG, OF WHITE PLAINS, NEW YORK.

CONCRETE MIXER.

Application filed July 9, 1919. Serial No. 309,654.

To all whom it may concern:

Be it known that I, WALTER G. CRAIG, a citizen of the United States of America, residing at White Plains, Westchester County, 5 and State of New York, have invented new and useful Improvements in Concrete Mixers, of which the following is a specification.

This invention relates to pavers or mixers of concrete.

10 The object of the invention is to provide apparatus whereby the material supplied to the mixer or paver may be expeditiously handled at a great saving of labor.

According to the present invention the 15 hand labor is largely dispensed with, the handling of the materials to be mixed is greatly expedited, the proportioning of the mixture is more accurately attained and there is always a supply of materials in condition to be charged into the mixer so that 20 no delays can arise from this source. This is accomplished by providing what may be termed a batch hopper wherein the materials may be placed in proper relative quantities 25 to form a batch for introduction into the mixing drum and a charging hopper adapted to deliver materials to the batch hopper and having a capacity of at least one and 30 preferably of two or more batches. The charging hopper is usually placed above the batch hopper so that its contents may be 35 gravitated into the batch hopper. This charging hopper, taking for example the case of road building where the material is deposited in stock piles along the highway, 40 may be kept replenished by means of a clam shell bucket or other suitable power or hoisting device, from the stock piles. Thus by applicant's invention the clam shell hoisting 45 bucket or other suitable hoisting means may be employed to supply material whereby the scarce hand labor may be dispensed with and further the employment of this character of hoisting and conveying means permits the charging hopper to be placed at 50 such a height that its contents may gravitate into the batch hopper.

In the accompanying drawings which 55 illustrate the invention—

50 Fig. 1 is a side elevation of a concrete mixer having a charging hopper partly broken away;

Fig. 2 is an end elevation of the appara-

tus of Fig. 1 looking in the direction of the arrow;

55 Fig. 3 is a top plan view of the apparatus of Figs. 1 and 2;

Fig. 4 is a perspective view of a fragment of the side of the batch hopper showing an 60 adjustable measuring slide; and

65 Fig. 5 is a top plan view of the apparatus of Fig. 4.

Referring to the drawings, the apparatus 70 comprises a frame 1 suitably supported on wheels 2 upon which the apparatus may be moved along a roadway. Mounted in the frame is a mixing drum 3, for mixing the concrete, which is rotatably supported upon rollers 4 which in turn are rotatably mounted upon the frame. The interior construction of devices of this character is well understood and need not be further referred to herein. The drum is rotated by means of a sprocket chain 5 passing over idlers 6 and 7 and driven by the sprocket wheel 8 secured 75 to a suitable power device such as an engine or motor within the housing 9. The sprocket chain passes about the circumference of the drum and engages with the sprocket teeth 10 formed on the drum.

80 The mixed material is delivered from the drum by means of a chute 11 mounted on the frame.

The batch hopper 12 is supported in suitable position by being bolted or otherwise 85 fixed to the frame. It has an inclined bottom 13 so that material therein will gravitate through the chute 14 into the mixing drum when the gate 15 is opened. Upon a wall as 16 of the batch hopper, are fixed two 90 angle irons 17 and 18 under the edges of which project the ends of a bar 18. In screw threaded engagement with the bar is a screw 19 having at its outer end wings 20, whereby the screw can be turned by the 95 fingers so as to advance it through the bar 18 and abut against the hopper wall 16 to secure the bar in position, or may be turned in the opposite direction to relieve the pressure of the screw on the wall and so permit 100 the bar to be adjusted vertically to vary the points to which material is to be filled into the hopper and so vary the proportioning of the batches.

105 Fixed to the frame 1 and mounted above the batch hopper so that its contents may

gravitate into the batch hopper, is a charging hopper 21 which is divided into two compartments by a vertical partition 22. This adapts the hopper for receiving broken stone in one compartment and sand in the other compartment but the compartments may be of any number and of any relative sizes according to the purposes desired to be served. The material is filled into the compartments from the upper open end of the hopper and the capacity of the charging hopper is at least two batches. The material of one compartment is restrained from flowing out of the hopper by means of a sliding gate 23, and from flowing out of the other compartment by means of a sliding gate 24. Upon opening either of the gates the contents of its respective compartment will gravitate into the batch hopper.

To trace the operation of the apparatus in one of its main functions, namely, the production of concrete for use in highway building, the sand and broken stone is piled in stock piles along the roadway. The apparatus is drawn along until it occupies the desired position. A clam shell hoist is then operated to fill sand into one compartment of the charging hopper and broken stone into the other compartment. The measuring bar 18 is then fixed in such position that when the material shall have been filled into the batch hopper up to the position occupied by the bar, a certain amount of material, say broken stone, for a batch will have been filled into the batch hopper. Accordingly the marking bar having been fixed as indicated, the gate controlling the compartment of the charging hopper containing broken stone is opened and the stone allowed to run into the batch hopper until it reaches the level of the bar, the gate of the broken stone compartment is then closed to shut off the supply of broken stone to the batch hopper. The bar may then be adjusted to a higher level such that when the sand has reached it, the right quantity of sand for a batch will be in the batch hopper. The measuring bar having been so adjusted, the gate for the sand compartment of the charging hopper may be opened and the sand allowed to run into the batch hopper until it reaches the level of the marking bar when it is shut off. While in the illustration just given it has been assumed that but one marking bar will be used and that this will be adjusted for the stone and sand as described, two bars might be employed, one for the stone level and the other for the sand level, and fixed in position so long as it was not desired to change the proportions of the batches.

The cement is always delivered in bags containing an accurate amount of cement so that the cement desired for the batch hopper may be emptied by hand directly from

the bags into the batch hopper and the quantity supplied is accurately determined by counting the number of bags.

When the right amount of material for a batch has thus been added to the batch hopper, the gate 15 may be opened when the whole will gravitate into the mixing drum to which water may be supplied in the usual way.

By making the charging hopper of large proportions in relation to the batch hopper as has been described, there is always an adequate supply of material on hand for introduction to the batch hopper and also there is always a place for the clam shell bucket to deposit its load without interfering with the accurate proportioning of the batch regardless of the amount of material carried by the clam shell.

While the invention has been illustrated in what is considered its best application, it may have other embodiments without departing from its spirit and is not therefore limited to the structure shown in the drawings.

What I claim is:—

1. In a mixing apparatus, a suitable supporting frame, a charging hopper adapted to initially receive material to be introduced into the apparatus from a shovel or the like in the upper part of the frame, said hopper having a plurality of compartments and a gate in the bottom of each compartment, a batch hopper fixed to said frame beneath said charging hopper in position to receive material directly from each of said compartments, said batch hopper having a gate at its lower end, measuring means associated with said hopper, and a rotatable mixing drum having a horizontal axis arranged to receive the materials from the batch hopper and rotatably mounted on said frame.

2. In a portable mixing apparatus, a suitable wheeled supporting frame, a charging hopper adapted to initially receive material to be introduced into the apparatus from a shovel or the like in the upper part of the frame, said hopper having a plurality of compartments and a gate in the bottom of each compartment, a batch hopper secured to said frame beneath said charging hopper in position to receive material directly from each of said compartments, said batch hopper having a gate at its lower end, a device vertically adjustable on the batch hopper for indicating the height of the materials thereon, and a rotatable mixing drum having a horizontal axis arranged to receive the materials from the batch hopper and rotatably mounted on said frame.

3. In a mixing apparatus, a suitable supporting frame, a charging hopper, adapted to receive material to be introduced into the apparatus from a shovel or the like, in the upper part of the frame, said hopper hav-

ing a plurality of compartments and a gate in the bottom of each compartment, a batch hopper fixed to said frame beneath said charging hopper in position to receive material directly from each of said compartments, said batch hopper having a gate at its lower end, and a rotatable mixing drum

having a horizontal axis arranged to receive the materials from the batch hopper and rotatably mounted on said frame. ¹⁰

In testimony whereof I have signed this specification this 7th day of July, 1919.

WALTER G. CRAIG.
